[57] ABSTRACT

One side of the heat exchanging plate has a marginal pressed groove for receiving the usual gasket, and both sides have pressed ridges extending side-by-side for crossing and contacting similar ridges on adjacent plates in a plate heat exchanger. The ridges on the same side of the plate as the marginal groove extend all the way to this groove, so that their end surfaces form parts of a side wall of the groove; and the ridges on the opposite side of the plate merge into plate portions between the latter ridges and the groove, these plate portions being situated between the two planes extending through the crests of the ridges on the two sides, respectively, of the plate.

HEAT EXCHANGING PLATE WITH PRESSED RIDGES

The present invention relates to heat exchanging plates of the kind having a pressed marginal groove for a gasket intended to seal between the plate and an adjacent heat exchanging plate in a plate heat exchanger, and also having on both sides pressed ridges extending side-by-side and intended to contact and cross similar ridges on adjacent plates in the heat exchanger, to serve as spacing means between the plates.

The contact points created between two plates of this kind in a plate heat exchanger must be able to transfer (without substantial deformation of the plate material) forces between the plates caused by clamping them together in a plate heat exchanger, and caused by pressure differences between the heat exchanging media treated in the heat exchanger. The strength of the plate at these contact points may therefore determine the thickness of the plate material, the form of the ridge cross-section, and the allowable pressure difference between the heat exchanging media in the plate heat exchanger.

The ridges formed in the plate by a pressing operation merge at their ends through sloping end portions into parts of the plate adjacent the said gasket groove and which are free from ridges. In plate parts of this kind, which are free from ridges and each of which extends across several ridges on the plate, there is generally no support against the adjacent plates in a plate heat exchanger. Those contact points of a plate which are situated nearest a part like this must therefore transfer greater forces than contact points located in the middle of a field of pressed ridges. Forces which really should be transferred by the plate part free from ridges must thus be transferred through said nearest contact points instead.

It is especially important that the ridges shall not be deformed at these contact points nearest the gasket groove, for the height of the ridges in these areas determines the thickness to which the gasket will be compressed.

Since the plate must be dimensioned and formed with regard to the greatest forces that may arise, the plate will have an optimum dimension only in the areas of the few contact points situated nearest the plate portions which are free from ridges, while the rest of the plate (i.e., the main part of the plate) will be over-dimensioned.

An object of the present invention is to provide a plate over which there is a more even distribution of the forces to be transferred through all of the contact points, so that the main part of the plate may have at least substantially an optimum dimension.

This object is fulfilled according to the invention by a plate on which the ridges situated on the same side of the plate as the gasket groove extend all the way to the gasket groove (i.e., their end surfaces form parts of the side wall of the gasket groove), while the ridges on the opposite side of the plate merge into plate portions located between the ridges and the gasket groove and which are situated between the planes extending through the crests of the ridges on both sides of the plate. With a construction of this kind it is possible, without changing the inclination of the end portions of the ridges, to obtain contact points substantially closer to the plate portions which are free from ridges than

was previously possible. In this way the force to be transferred through these contact points can be reduced, and the main part of the plate need not be over-dimensioned as much as heretofore.

The invention will be described in more detail below with reference to the accompanying drawings.

In the drawings,

FIGS. 1 and 1a are face views of two plates of the kind involved here;

FIG. 2 is a fragmentary sectional view of two such plates as paired to form points of contact between them in a plate heat exchanger;

FIG. 3 is a face view of a further plate of the kind involved here;

FIGS. 4a and 4b are plan and cross-sectional views, respectively, of part of a previously known plate;

FIG. 5a is a plan view of part of a plate incorporating various forms of the invention; and

FIGS. 5b, 6, 7, 8 and 9 are cross-sectional views on the lines VII—VII, VIII—VIII, IX—IX, X—X and XI—XI, respectively, in FIG. 5a.

The two plates 1 and 2 as shown in FIGS. 1 and 1a are identical (not necessary), and one of them is turned 180° relative to the other in the plane of the drawing. Each plate has ridges formed on both sides by a pressing operation. The ridges visible in FIGS. 1 and 1a are designated 3. The ridges situated on the other side of each plate are formed by the back sides of the troughs located between the ridges 3 and which are designated 4. The two plates have openings 5—8 serving as inlets and outlets for two heat exchanging media flowing to and from respective plate interspaces which are formed when several plates are assembled in a conventional manner in a plate heat exchanger.

In FIG. 2 there are shown fragments of the plates 1 and 2 placed relative to each other as in a plate heat exchanger. As can be seen, contact points 9 are created between the plates, where the ridges of the plates cross and contact each other.

Normally, plates of the kind shown in FIGS. 1 and 1a are not entirely covered by ridges formed by pressing. In FIG. 3 there is shown with broken lines a narrow portion 10 of a plate. This narrow portion 10, extending along the long sides of the plate and close to the inlet and outlet openings 5—8, is free from ridges for the reason that the plate in this area has a groove for a so-called marginal gasket. The latter (not shown) is intended to close from the surrounding atmosphere the interspace formed between the two plates when they abut each other in a plate heat exchanger. The area surrounded by the narrow portion 10 is provided with the ridges (not shown).

A groove 22 is pressed near the edge of the previously known plate shown in FIGS. 4a and 4b, this groove serving to receive a marginal gasket (not shown). A plane portion of the plate, situated between the groove 22 and the ridges 3 and 4 pressed in the heat transferring portion of the plate, is designated 10. As can be seen from the drawing (FIG. 4b), the crests of the ridges 3 are situated in the same plane as the said portion 10, and the ridges 3 therefore may be said to extend all the way to the groove 22. The ridges 4 on the other side of the plate extend only to the portion 10, however, and the ridges 4 therefore will determine how near the gasket groove 22 it is possible to obtain contact points between two plates in a plate heat exchanger. The smallest distance between the bottom of

the gasket groove 22 and a contact point of this kind is marked C in FIG. 4b. The greater this distance is, the greater the unsupported plate portion will be, and the greater the force to be transferred at the contact point.

The plan view of FIG. 5a shows five different embodiments I-V of the region of the gasket groove in a plate according to the invention. The ridges on the upper face of the plate are designated 18, while the ridges on the lower face are designated 19, the latter ridges being formed by the valleys between the upper ridges 18. The gasket groove is designated 23.

When comparing FIG. 4a and FIG. 5a, it will be noted that the distance in the plate of FIG. 5a between the ends of the ridges 19 and the gasket groove 23 (in all embodiments I-V) is smaller than the distance between the ends of the ridges 4 and the groove 22 in the prior art plate of FIG. 4a. This is a result of the fact that the portion 10 in the area between the ends of the ridges 4 and the gasket groove 22 (FIGS. 4a and 4b) has been displaced to a level half way between the two planes extending through the crests of the ridges 18 and 19, respectively, on opposite sides of the plate. In the embodiment V, the width of this portion (designated 24 in FIG. 5a) has been kept as large as the width of the corresponding portion 10 in FIG. 4a while in the other embodiments I-IV the width of the same portion 24 has been reduced to a minimum. In FIG. 5b there is shown a cross-section of the embodiment V along the line VII-VII in FIG. 5a, while in FIG. 6 there is shown the corresponding cross-section along the lines VIII-VIII in FIG. 5a, which is common to the other embodiments I-IV. In FIG. 5b, the smallest distance obtainable between the bottom of the gasket groove 23 and the nearest contact point between two plates in a plate heat exchanger is marked D. As can be seen, this distance D is smaller than the corresponding distance C in the prior art plate of FIGS. 4a and 4b. A broken line 25 in FIG. 5b shows where the ridges 4 of the prior art plate end at the region of the gasket groove. Consequently, 40

the contact points nearest the gasket groove 23 in the plate according to the invention do not need to transfer such great forces as the contact points nearest the gasket groove 22 in the prior art plate.

- 5 In FIG. 5a, the embodiments II, III and IV are shown with grid-like areas 26, 27 and 28, respectively. These areas are other portions of the plate which, like the portion 24, are situated at a level half way between the planes extending through the crests of the ridges 18 and 10 19 situated on opposite sides of the plate. In the embodiments II and III, these areas 26 and 27, respectively, are directly connected in the same plane with the portions 24, while in the embodiment IV there is a small interspace between the area 28 and the portion 15 24.

I claim:

1. A heat exchanging plate having a peripheral part provided with a pressed groove for receiving a gasket adapted to seal between the plate and an adjacent heat 20 exchanging plate in a plate heat exchanger, said groove having opposing side walls which are substantially continuous, the plate also having on each side thereof pressed ridges extending in side-by-side relation for crossing and contacting similar ridges on adjacent plates in said heat exchanger to form spacing means between the plates, the plate being characterized in that the ridges located on the same side of the plate as the gasket-receiving groove extend all the way to said groove, whereby the end surfaces of said sameside ridges form parts of said side wall of said groove, the ridges on the opposite side of the plate merging into plate portions between said opposite-side ridges and said groove, said plate portions being situated between the two planes extending through the crests of said same-side and said opposite-side ridges, respectively.

2. A heat exchanging plate according to claim 1, in which said plate portions are situated half way between said two planes.
